UNITED STATES PATENT OFFICE.

EDWARD G. WATKINS, OF GARDNER, MASSACHUSETTS, ASSIGNOR TO SAMUEL J. SHIMER & SONS, OF MILTON, MASSACHUSETTS.

BIT-ADJUSTER FOR ROTARY CUTTER-HEADS.

1,032,636.

Specification of Letters Patent.

Patented July 16, 1912.

Application filed February 7, 1911. Serial No. 607,190.

To all whom it may concern:

Be it known that I, EDWARD G. WATKINS, of Gardner, in the county of Worcester and State of Massachusetts, have invented a certain new and useful Improvement in Bit-Adjusters for Rotary Cutter-Heads, and do hereby declare that the following is a full, clear, and exact description thereof.

In the rotary cutter head which is the subject of the Shimer Patent No. 874,871, December 24, 1907, the bit or blade adjusting means consists of a simple screw located at the back or inner side of the bit holder which is accessible only by the removal of the bit holder from the cutter head.

The object of my invention is to provide a bit adjusting device for cutter heads of the type referred to, which will be conveniently accessible at all times without the removal of the bit holder from the cutter head and which will possess other advantages, and to this end my invention consists in the device constructed substantially as hereinafter specified and claimed.

25 In the accompanying drawings—Figure 1 is a perspective view of a rotary cutter head embodying my invention; Fig. 2 a section thereof on a plane transverse to the axis of revolution, but of only a fragment of the head; Fig. 3 a section on the line 3—3 of Fig. 2; and Fig. 4 a detail view in perspective of one of the bit holders removed from the cutter head.

The type of cutter head to which my invention relates comprises a cylindrical body 10 having an axial hole or opening for the shaft or mandrel, and having in its periphery a series of longitudinally extending channels or recesses 11, in each of which is placed one or more bit holders 12, in the form of a metal block that is provided with a bit receiving slot 13 extending from one edge inward nearly to the opposite edge so as to constitute a clamp for the bit 14 under the action of one or more bolts 15 whose threaded shank enters a threaded opening 16 in the bit holder while its head is adapted to engage the adjacent side wall of the cutter head recess when the bolt is turned in the direction as for unscrewing, and thereby exerts a thrust upon the bit holder which produces a pinching or clamping effect of the two portions of the bit holder separated by the slots 13 upon the bit, as well as, at 50 the same time securely holds the bit holder

in its recess in the cutter head. In the embodiment of my invention that I have selected for illustration, there are two bolt holes 16, one near each end of the bit holder and in a thickened portion of the bit holder 60 through which said screw holes pass, and situated between said screw holes in said thickened portion 17 is an opening 18 which forms a bearing for the outer end of a screw 19, the inner end of which has a bearing in a 65 hole 20 in the cutter head body, the threaded portion 21 of the screw being of somewhat greater diameter than the inner end that has its bearing in the hole 20 and extending between said inner end and the inner side of 70 the thickened portion of the bit holder. Contiguous to the outer end of its threaded portion 21, the screw has a collar or annular enlargement 22 that forms a thrust bearing to prevent endwise movement of the screw 75 outward while endwise movement of the screw inward is prevented by the shoulder that is formed at the inner end of the screw by the reduced bearing end thereof in the opening 20. Thus, though the screw 19 is free to 80 revolve, it is prevented from endwise movement in either direction. Mounted upon the threaded shank 21 of the screw is a nut 23 having a radial projection or finger 24 that projects through a slot 25 merely wide 85 enough to accommodate it in the bit holder and bears against the inner edge of the blade 14. The nut 23 being prevented from rotating by the engagement of its lug 24 with the sides of the slot 25, it is compelled by the 90 rotation of the screw to traverse along the screw, and, of course, by the contact of the lug 24 with the inner edge or heel of the blade 14, the blade 14 will be moved outward when the direction of rotation of the 95 screw is such as to cause an outward movement of the nut. It will thus be seen that I have provided a simple and most efficient blade adjusting device which will positively hold the blade in its adjusted position, and 100 as the outer end of the screw 19 is exposed so that it is at all times accessible, such adjustment of the blade as is necessary may most conveniently and quickly be effected.

Instead of the tongue or rib 7 on the inner 105 side of the bit holder which is employed in Patent No. 874,871 to prevent the bit holder dropping out of the body or cylinder 10 when the clamping bolts are loose, I provide in the rear wall of the holder a threaded 110

hole 26 into which is screwed the inner end of a screw 27 passing through a hole 28 extending inward from the periphery of the cylinder or body 10. This arrangement is 5 preferable to the rib and groove device of Patent No. 874,871, because it does not require as does the rib and groove arrangement that the bit holder shall be slid endwise through the recess in the cylinder or 10 body in applying it to or removing it therefrom, for which operation it is necessary to take the cutter head out of the planer. With the screw device, evidently, the operation of applying and removing the bit 15 holder to the head can, therefore, be much more conveniently and easily performed. The cylinder or body 10, shown in the drawings, is provided with the rib-receiving grooves so that such head, if desired, can be 20 used with bit holders having ribs, as in the patent above mentioned.

Having thus described my invention what I claim is—

1. The combination of a cutter head having 25 a peripheral recess, a bit holder in said recess having an outwardly opening bit-receiving slot, a screw having a bearing in a thickened wall of said bit holder with its operating end outwardly exposed, and a nut 30 on the screw engaging the inner end of the bit, confined to travel along the screw by the walls of a slot extending inwardly from the thickened portion of the bit holder.

2. The combination of a cutter head having 35 a peripheral recess, a bit holder in the form of a block having a bit-receiving slot that extends outward, a screw having a bearing in said block at one side of said slot and a bearing in the cutter head, and a nut

on the screw having a bit-engaging lug, the 40 lug projecting through a slot in the contiguous wall of the block and engaging the sides thereof to prevent turning of the nut.

3. The combination of a cutter head having 45 a peripheral recess, a bit holder in said recess in the form of a block having a bit-receiving slot that extends outward, the block, toward its outer end, having its wall contiguous to the bit-receiving slot thickened, a screw having a bearing in said thickened 50 wall with its operating end outwardly exposed, a nut on the screw engaging the inner end of the bit, said nut playing back and forth in a slot in the block extending inwardly from the thickened portion of the 55 block wall, and a bolt passing through a threaded opening on the thickened wall at each side of said adjusting screw engaging the bit at one end, and the contiguous wall 60 of the cutter head recess at the other end.

4. The combination of a cutter head having 65 a bit holder receiving recess extending from the periphery of the cutter head inward, a bit holder having bit-engaging members on opposite sides of the bit, a bolt engaging an opening in one of said bit-engaging members, and adapted to bear against the contiguous wall of said recess, and a bit holder engaging part situated in an opening 70 extending inward from the periphery of the head and entering a hole in the bit holder.

In testimony that I claim the foregoing I have hereunto set my hand.

EDWARD G. WATKINS.
